UNITED STATES PATENT OFFICE.

SENECA W. PELSUE AND ERNEST W. CUDWORTH, OF ARLINGTON, VERMONT.

LOCK.

Application filed October 18, 1921. Serial No. 508,452.

To all whom it may concern:

Be it known that SENECA W. PELSUE and ERNEST W. CUDWORTH, citizens of the United States of America, residing at Arlington, in the county of Bennington and State of Vermont, have invented certain new and useful Improvements in Locks, of which the following is a specification.

Our invention relates to new and useful improvements in means for preventing theft or unauthorized use of motor vehicles.

The object of our invention is to provide an effective means for locking the ring gear of the differential mechanism against rotation and consequently prevent rotation of the rear or driving wheels.

Other and further objects of our invention will be in part obvious and in part described as the specification is proceeded with.

In the accompanying drawings forming part of this specification wherein we have illustrated a preferred embodiment of our invention:

25 Figure 1 is a transverse section through the differential casing and lock;

Figure 2 is an end elevation of the lock showing one half of the casing removed;

30 Figure 3 is a side elevation of the lock in engagement with the ring gear;

Figure 4 is a transverse section on the line 4—4 of Figure 5;

Figure 5 is a section on line 5—5 of Figure 4;

35 Figure 6 is a section on the line 6—6 of Figure 4; and

Figure 7 is a longitudinal sectional view through the cylinder lock.

Referring more particularly to the drawings, 1 and 1^a denote the rear axles of an automobile and 2 and 2^a the usual two part differential and rear axle housing. Enclosed within the housing 2 is the differential casing 3 provided with a flange 4 to which is suitably secured the ring gear 5 as by means of bolts 6. It will be understood that the ring gear 5 rotates with the differential casing 3 and is driven by the usual drive shaft (not shown) meshing with the teeth 7 of the ring gear. It will also be understood that the differential casing 3 houses the compensating gears (not shown) and the gears (also not shown) on the inner ends of rear axles 1 and 1^a.

55 As the parts above briefly referred to are all old and well known further and detailed

description thereof is deemed unnecessary.

Fixedly mounted in or cast integral with the half 2^a of the differential and rear axle housing is a preferably rectangular open ended boxing 8, within which is slidably mounted a rectangular locking plunger or member 9, having a segmental shaped offset end 10, formed with teeth 11, adapted to mesh with the teeth 7 of ring gear 5 when the plunger 9 is moved inwardly against the tension of springs 20 about to be described.

The outward movement of the plunger 9 to disengage it from the ring gear is effected by means of a pair of oppositely disposed coil springs 20 connected at their outer ends to pins 21 secured to the open ended boxing 8 and at their inner ends to pins 22 connected to the plunger 9, the pins 22 extending through slots 23 formed in the boxing 8 for the purpose of permitting limited reciprocal movement of the boxing.

When the plunger 9 is in its innermost or locking position a pair of locking pins 24 arranged to slide in recesses 25 formed in the plunger 9, on opposite sides of the bore 11 thereof, will have their reduced ends forced into the openings 26 in the boxing 8 by means of coil springs 27 thus effectively locking the plunger against withdrawal from locking engagement with the ring gear. To unlock the plunger it is necessary to withdraw the spring pressed pins 24 from the recesses 26 in the boxing 8. This is accomplished as follows:

90 A lock cylinder 12 is fixed in the outer end of the bore 11 of the plunger and adapted to move therewith. Secured within the lock cylinder 12 is a sleeve 28, both the sleeve and cylinder being formed with registering recesses adapted to accommodate the ordinary spring pressed tumblers 29. These tumblers normally extend into a narrow key receiving slot 30 formed in the outer end of a connecting bar 31 rotatably 95 and slidably mounted in the sleeve 28, the inner end of the bar 31 being of rectangular shape to snugly seat in the rectangular opening 32 of a cylindrical latch member 33 formed with longitudinally oppositely disposed ribs 34. These ribs are adapted to engage shoulders 35 on the pins 24 and withdraw the pins from the recesses or openings 26 in the boxing 8, when the latch member 33 is turned in a clockwise direction. 100 It is obvious from an inspection of Figure 7 that when the key 36 is inserted in the

slot 30, the spring pressed tumblers 29 will be forced out of the slot 30, thus permitting the latch member 33 to be turned to release the plunger 9. When this occurs the springs 5 20 will withdraw the teeth 11 of the plunger from engagement with teeth of the ring gear.

From the foregoing it is obvious that the differential can be locked by the operator 10 merely pushing inwardly on the plunger 9 or the cylinder lock secured thereto, and that the only operation necessary to unlock the device is the insertion of the proper key in the slot 30 and sufficient turning of the 15 key in a clockwise direction to release the pins 24.

Having thus described our invention what we claim as our invention is:

In locking mechanism for motor vehicles 20 having a differential mechanism including a ring gear, a housing for the differential

mechanism, a boxing fixed to said housing, a toothed plunger slidably but nonrotatably mounted in said boxing, said boxing having recesses therein, spring pressed pins carried by said plunger adapted to enter said recesses to lock said plunger in engagement with said ring gear when said plunger is pushed forwardly in said boxing, a rotatable latch member in said plunger, a cylinder lock in said plunger, a bar connected at one end to and rotatable with said latch member, and means for rotating said bar to release spring pressed pins.

In testimony whereof we affix our signatures in presence of two witnesses.

SENECA W. PELSUE.
ERNEST W. CUDWORTH.

Witnesses:

GEORGE D. HOWARD,
EDWARD E. PHILLIPS.
